UNITED STATES PATENT OFFICE.

JOHN B. DAVIDS, OF NEW YORK, N. Y.

IMPROVEMENT IN MALLETS.

Specification forming part of Letters Patent No. 117,609, dated August 1, 1871.

To all whom it may concern:

Be it known that I, JOHN B. DAVIDS, of the city and State of New York, have invented new and useful Improvements in Mallets, of which the following is a specification:

My invention relates to a wooden mallet surrounded with a metallic shell or case formed in two parts, slightly rounded and tapering toward each face. Thereads are cut or cast thereon, whereby rings or nuts having a corresponding thread are made to fit the outside ends of the shell for the purpose of contracting the same and compressing the mallet. The object of my invention is to make a more perfect mallet than heretofore made.

The objections to certain mallets with metallic bodies and wood faces are that the cost of making the two faces is equal to making two ordinary mallets; and, again, the faces, being driven into the metallic shell, soon become loose, split, and then fall out, there being nothing to hold the pieces in place. Another plan is to use a metallic box-shaped shell, its ends being open to receive the wood faces, with cap on one side to compress the wood faces. The manner of securing the square face made of wood is very imperfect, as the cap compresses the wood against the opposite side only, while two sides may be loose. Thus the wood soon splits, must be wedged in, or comes out entirely. The old style of shrinking rings upon mallets and the trouble experienced in their continually falling off are also well known.

By my plan I have overcome all known objections, and construct a more desirable and ornamental mallet than has heretofore been produced.

Figure 1 represents my improved mallet. Fig. 2 represents the shell or case. Fig. 3 represents the rings or nuts.

Fig. 1, A represents the wood part of the mallet; B, the handle; C, the shell or case; D, rings or nuts; E, threads or screw.

To enable others skilled in the art to make my invention, I will describe its formation.

I form my mallet from any suitable tough wood by turning in the usual manner. The shell

is made from any suitable metal, as wrought-iron, brass, various similar compositions, but prefer to use good malleable iron for convenience and cheapness. The shell is made in two pieces or halves of suitable thickness, preferring, however, three-sixteenths of an inch for the ordinary size. It should, however, be increased in thickness as the size of the mallet is increased. The form should be somewhat barrel-shaped, and may be made very ornamental. Various designs emblematic of different orders of societies may be carved or engraved upon the shell, when desired for use as a gavel by the presiding officer. These shells or cases may be cast in molds or may be forged. The rings or nuts may be made of the same material and in the same manner as the shell. Threads should be cut or cast on the inside diameter of these rings to fit a corresponding thread on the outside of the shell at each end of the same. The wood part should be turned about one-sixteenth of an inch larger than the inside diameter of the case, to allow contracting the cases when the wood part shrinks. A swell is formed on the handle which partly enters the hole or eye in the mallet, the eye being counter-bored for the purpose previously to receive it, the shell being so formed that one-half of a circle of suitable diameter is prepared in each part of the shell to close over the neck of the handle and outside of the projection while in position. Thus put together, the rings or nuts may be turned around in the proper direction to contract the shell and compress the wood firmly. Thus the wood is prevented from splitting and the handle secured in place.

The manner of using my invention is so familiar that an explanation is unnecessary.

I claim as my invention—

The rings or nuts D and shells or case C C, when made in two or more parts and applied to mallets, for the purpose as herein specified.

JOHN B. DAVIDS.
